UNITED STATES PATENT OFFICE.

ALBERT G. KOPACKI, OF BAY CITY, MICHIGAN, ASSIGNOR OF ONE-HALF TO FRANK C. LEARMAN, OF ESSEXVILLE, MICHIGAN.

SHOE-CLEANING MACHINE.

1,101,194.

Specification of Letters Patent. Patented June 23, 1914.

Application filed September 8, 1913. Serial No. 788,619.

To all whom it may concern:

Be it known that I, ALBERT G. KOPACKI, a citizen of the United States of America, residing at Bay City, in the county of Bay 5 and State of Michigan, have invented certain new and useful Improvements in Shoe-Cleaning Machines; and I do hereby declare the following to be a full, clear, and exact 10 description of the invention, such as will enable others skilled in the art to which it appertains to make and use the same.

My invention relates to improvements in shoe cleaning machines, and its object is to provide a device of this character which will 15 clean the shoe upon the foot of the wearer by the simple operation of rocking the foot to and fro, to provide a device simple in construction and effective in operation, and to provide the same with other new and use- 20 ful features hereinafter more fully described and particularly pointed out in the claims, reference being had to the accompanying drawing in which:

Figure 1 is an elevation of a device embodying my invention with a shoe in operative position thereon, one position of the device being shown in solid lines, while the reverse position is shown by dotted lines; and Fig. 2 is a plan view of the same with 30 the shoe removed therefrom.

Like numbers refer to like parts in all of the figures.

1 is a pedestal provided with a base 2, by which it may be rigidly attached to the floor. 35 A foot support 4 is pivotally attached near its center as at 5, to the upper end of the pedestal 1 and is provided with a heel stop 7 to aid in retaining the shoe in proper position during the operation. A pair of du- 40 plicate double bell crank levers 9 are pivotally connected at opposite sides of the pedestal near the base, and their upwardly ex- 45 tending arms 8 are provided with hinged ex- 50 tensions 8^a which carry at their upper ends the side brushes 12. Springs 35 are pro- 55 vided which normally draw the upper ends of the extensions 8^a toward each other, but permit them to spread to accommodate dif- 60 ferent widths of shoes, and the brushes 12 65 are pivotally attached to the said extensions 8^a so that they will automatically align 70 themselves with the surfaces which they 75 contact. These levers are rocked by movement

of the foot support 4 through the connecting rod 31, one end of which is attached near 55 the toe of the said support 4, and the other end to the arm 10 of each double bell crank 9. An arm 14 is pivotally connected as at 15 to the pedestal 1 near its upper end and extends laterally from the said pedestal and 60 is provided with an extension 14^a pivotally connected at 36 to the arm and this extension carries a heel brush 16 pivotally attached as 17. A spring 37 normally draws the ex- 65 tension 14^a upward relative to the arm 14, and a pin 39 engages a stop 38 to limit this upward movement. This construction al- 70 lows the extension 14, carrying the brush, to yield downward when sufficient pressure to overcome the spring 37 is applied to the brush. This brush is caused to move up- 75ward at a greater speed than the heel end of the foot support 4 by being connected by the connecting rod 18 with the arm 11 of the double bell crank 9. An arm 34 projects 80 forward from the toe end of the foot sup- 85 port 4 and carries on its forward end a lever 24, the lower end of which is attached by the connecting rod 21 to the arm 8 of the double bell crank 9. The movement of the 90 foot support, together with the double bell crank, causes the lever 24 to oscillate and this lever carries at its upper end a hinged extension 26, which supports the toe brush 29 pivotally connected as at 30 to the said 95 extension. A stop 26^a limits the downward movement of this extension relative to the lever 24, and a spring 28 yieldably holds the extension against the stop.

The operation of the device is as follows:— 100 The operator places his foot, having a shoe to be cleaned thereon, upon the foot sup- 105 port 4 and adjusts it thereon by means of the heel stop 7. He then rocks the support upon its pivot 5 and this movement is trans- 105 mitted through the above described connect- 110 ing rods to the levers which carry the brushes, and these brushes are caused to move in the following manner to clean the shoe: The side brushes 12 oscillate longi- 115 tudinally of the shoe, brushing the dirt from the sides thereof. The heel brush 16 rises and engages the heel of the shoe and moves vertically thereon, being maintained in en- 120 gagement by the spring 37, the toe brush 29 125 engages the upper surface of the toe of the

shoe and is retained in engagement by the spring 28 and moves longitudinally of the shoe at each oscillation of the lever 24.

What I claim is:—

- 5 1. A shoe cleaning machine, comprising a pivoted shoe support, a pair of bell crank levers having upwardly extending arms and horizontal arms arranged to move in planes longitudinal of the shoe support, brushes 60
- 10 on the upwardly extending arms of the said bell crank levers to brush the sides of a shoe and connecting rods attached to the horizontal arms of the bell cranks and to the shoe support. 65
- 15 2. A shoe cleaning machine, comprising a pivoted shoe support, a pair of bell crank levers having horizontal arms and also provided with yieldable upwardly extending arms arranged to move longitudinally of the 70
- 20 shoe support, brushes pivotally attached to the upper ends of said yieldable arms to brush the sides of a shoe and connecting rods attached to the horizontal arms of the bell cranks and to the shoe support. 75
- 25 3. A shoe cleaning machine, comprising a pivoted shoe support, a pivoted lever, a brush on the free end of said lever, and means including the lever actuated by rocking the shoe support to raise the brush into 80
- 30 contact with the heel of a shoe on the said support and to move the brush vertically on the shoe. 85
- 35 4. A shoe cleaning machine, comprising a pivoted shoe support, a yieldable pivoted lever, a brush pivotally attached to the free end of said lever, and means including the lever operated by rocking the shoe support to bring the brush into contact with the heel 90
- 40 of a shoe thereon and to move the brush vertically on the shoe. 95
- 45 5. A shoe cleaning machine, comprising a pivoted shoe support, a lever pivotally attached to the said support, a brush on the upper end of the lever, and means including the lever actuated by rocking the shoe support to move the brush into contact with the upper surface of a shoe on the support and to move the brush longitudinally of the shoe. 100
- 50 6. A shoe cleaning machine, comprising a pivoted shoe support, a yieldable lever pivotally attached to the said support, a brush pivotally attached to the yieldable lever, and means including the lever operated by rocking the shoe support to move the brush into contact with the upper surface of a shoe thereon. 105
- 55 7. A shoe cleaning machine comprising a pivoted shoe support, a pair of upwardly 110

extending arms mounted to move longitudinally of the shoe support, brushes on said arms to brush the sides of the shoe, and means connected to said arms and said support adapted to operate said arms upon pivotal movement of the shoe support. 115

8. A shoe cleaning machine comprising a pivoted shoe support, a pair of upwardly extending yieldable arms mounted to move longitudinally of the shoe support, brushes on said arms to brush the sides of the shoe, and means connected to said arms and to said support to operate said arms upon pivotal movement of the shoe support. 120

9. A shoe cleaning machine comprising a pivoted shoe support, a brush supporting means, and means including the brush supporting means actuated by pivotal movement of the shoe support to operate the brush vertically over the heel of the shoe. 125

10. A shoe cleaning machine comprising a pivoted shoe support, a brush supporting means, a brush on the brush supporting means, and means including the brush supporting means actuated by the pivotal movement of the shoe support to move said brush into contact with the upper surface of a shoe on the support. 130

11. A shoe cleaning machine comprising a pivoted shoe support, a brush supporting means, a brush on the brush supporting means, and means including the brush supporting means actuated by the pivotal movement of the shoe support to move said brush into contact with the upper surface of a shoe on the support and to move the brush longitudinally of the shoe. 135

12. A shoe cleaning machine, comprising a pivoted shoe support, a lever pivotally attached to said support, a brush on the upper end of the lever, and means including the lever actuated by rocking the shoe support to move the brush into contact with the upper surface of a shoe on the support. 140

13. A shoe cleaning machine, comprising a pivoted shoe support, a yieldable lever pivotally attached to the said support, a brush pivotally attached to the yieldable lever, and means including the lever operated by rocking the shoe support to move the brush into contact with the upper surface of a shoe thereon. 145

In testimony whereof I affix my signature in presence of two witnesses.

ALBERT G. KOPACKI.
